COMBINED CHECK MARKER AND FOUNTAIN PEN OR SIMILAR ARTICLE

Filed Oct. 28, 1937

Fig. 3. Inventor
Giuseppe Donato

UNITED STATES PATENT OFFICE

115,916

DESIGN FOR A COMBINED CHECK MARKER AND FOUNTAIN PEN OR SIMILAR ARTI- CLE

Giuseppe Donato, Philadelphia, Pa.

Application October 28, 1937, Serial No. 72,488

Term of patent 7 years

To all whom it may concern:

Be it known that I, Giuseppe Donato, a citizen of the United States, residing at 700 South Washington Square, Philadelphia, in the county of Philadelphia and State of Pennsylvania, have invented a new, original, and ornamental Design for a Combined Check Marker and Fountain Pen or Similar Article, of which the following is a specification, reference being had to the accompanying drawing, forming part thereof.

Fig. 1 is a front elevational view of a combined check marker and fountain pen showing my new design.

Fig. 2 is a side view thereof, and

Fig. 3 is an enlarged view of the cap portion.

I claim:

The ornamental design for a combined check marker and fountain pen or similar article, as shown.

GIUSEPPE DONATO.
